UNITED STATES PATENT OFFICE

134,386

DESIGN FOR A PICTURE FRAME

Francis E. Blod, New York, N. Y., assignor to
Photo Frame Company, Inc., Long Island City,
N. Y., a corporation of New York

Application October 1, 1942, Serial No. 108,383

Term of patent 7 years

To all whom it may concern:

Be it known that I, Francis E. Blod, a citizen of the United States, residing at New York, in the county of New York and State of New York, have invented a new, original, and ornamental Design for a Picture Frame, of which the following is a specification, reference being had to the accompanying drawing, forming part thereof, in which:

Fig. 1 is a front view in elevation of the frame showing my new design;

Fig. 2 is a fragmentary rear view in elevation;
Fig. 3 is an enlarged cross section taken on the line 3—3 of Fig. 1; and

Fig. 4 is an enlarged cross section taken on the line 4—4 of Fig. 1.

It is understood that the design disclosed in full lines is to be continued around the frame.

I claim:

The ornamental design for a picture frame, as shown and described.

FRANCIS E. BLOD.
